UNITED STATES PATENT OFFICE

CHRISTOPHER FREDERICK WEBB, OF KENTON, MIDDLESEX, ENGLAND, ASSIGNOR, BY MESNE ASSIGNMENTS, TO THE BELL PUNCH AND PRINTING CO. LIMITED, OF UXBRIDGE, MIDDLESEX, ENGLAND

PRINTING MACHINE

Application filed March 9, 1928, Serial No. 260,268, and in Great Britain April 12, 1927.

This invention relates to a motor driven printing machine of the kind in which portions of a strip or web are printed to serve as railway admission or other tickets, the printing thereof being effected by means of a single rotary type-cylinder co-operating revolvably with an impression roller.

A machine of this kind is described in the specification of the British Patent No. 277,147 adapted for printing tickets for a single denomination or fare only, including numbering and dating, the impression roller therein being, however, arranged to be moved to press the web or ticket into contact with the type-cylinder for effecting the printing of each group of printing matter.

The main object of the present invention is to adapt a machine of the described type, and having a movable impression roller, for printing tickets of different denominations or fares, and to this end the printing surfaces for the different denominations of tickets are arranged around the type-cylinder in alignment with each other and with dating and/or numbering printing surfaces where employed and manually operable mechanism is provided for selecting any one of the said denominational printing surfaces for printing in conjunction with the said dating and/or numbering printing surfaces.

The manually operable means is preferably such as to allow of the printing and delivery in succession of more than one ticket of each denomination the machine is capable of printing.

In a suitable arrangement for carrying out the invention I make use of manually operable selecting mechanism comprising a series of key-levers, corresponding with the printing surfaces for the different denominations of tickets, and I arrange a series of cams around the shaft of the type-cylinder corresponding to the said printing surfaces, respectively, mechanism being provided whereby the operation of any key-lever will bring the impression roller into operative connection with the cam of the said series corresponding to the said key-lever to print a ticket when the selected printing surface arrives in the printing position.

The shaft of the type-cylinder also carries a cam corresponding with the numbering printing surface on the said cylinder for effecting the inking of such surface and the operation of the impression roller and also another cam functioning in a similar manner in connection with the dating mechanism where such latter mechanism is employed. The latter cam is preferably arranged so that it can be put out of action or moved so that it functions when the dating printing surface is out of the printing position.

To allow of the operation of one key-lever only at a time, means are provided whereby such operated key-lever will cause the paths of the remaining key-levers to be obstructed.

The key-levers are arranged in connection with means whereby, when one of them is operated, it will start the driving motor and automatically stop the latter when the type-cylinder has made a complete rotation for the printing and delivery of a single ticket, the said means returning the operated key-lever to its initial or normal position.

For printing and delivering in succession more than one ticket of each denomination, the key-levers support one or more additional key-levers designed when one of them is operated to effect also the operation of the said supporting or main key lever, the means for stopping and starting the motor and returning the said main key lever to its initial position being so constructed and arranged as to allow the type-cylinder to rotate and effect the printing and delivery of two or more tickets of one denomination before stopping the motor and returning the operated key-levers to their initial or normal position.

Means are provided for severing each length from the strip or web to form a ticket prior to the printing thereof and means are provided for delivering each printed ticket so as to protrude from a slit in the case of the machine in position for use.

A numerator or counter is advantageously arranged in connection with each main key-lever to record the number of operative depressions thereof, together with an additional numerator or counter to record the sum of the

numbers indicated by the said numerators or counters. For operating all of the said numerators or counters, a cam is arranged on the shaft of the type-cylinder, which cam moves the operating arms of the numerators controlled by the main key-levers and also the operating arm of the additional numerator sufficiently to effect a record in the latter case, but not in the former, means operating by the operation of the said key-levers being employed whereby the said cam will also move the operating arms of the numerators controlled by the said main key-levers to effect a record of their operation.

To enable the invention to be fully understood I will describe it by reference to the accompanying drawings, in which:

Figure 1 is a sectional side elevation of a printing machine constructed in accordance with the invention.

Figure 2 is a plan view thereof with the top removed and with portions broken away to disclose underlying mechanism.

Figures 3 and 4 are, respectively, sections on the lines 3—3 and 4—4, Figure 1.

Figure 5 is a sectional side elevation of the machine looking towards the side opposite to that shown in Figure 1.

Figure 6 is a section on the line 6—6, Figure 5.

Figure 7 is a development of the surface of the drum carrying the cams for effecting the inking and printing operations.

Figure 8 is a perspective view, hereinafter referred to, of a portion of the mechanism.

Figure 9 is a view of the ticket delivery mechanism similar to that shown in Figure 1, but showing a ticket delivered into position for use.

Figure 10 is a view similar to a portion of Figure 5, but showing a different position of some of the parts.

Figure 11 is a view similar to Figure 1, but showing a different position of some of the parts.

a is the type-cylinder, which is carried by the shaft *b* mounted in bearings *b*¹, *b*¹ in the machine frame comprising the side-plates *b*² and tie-bars *b*³ enclosed in the machine case *b*⁴, the said type-cylinder being designed to be driven, by an electric motor, as hereinafter described, a complete revolution to print each ticket. This cylinder *a* is shown as being provided with eight printing surfaces *a*¹, *a*², *a*³, *a*⁴, *a*⁵, *a*⁶, *c*, *d* aligning in a direction around the cylinder *a*, the printing surfaces *a*¹ to *a*⁶ serving to indicate different denominations or fares, whilst the printing surfaces *c*, *d* are, respectively, those of numbering and dating mechanisms which are shown of the rotary wheel type, the numbering mechanism carrying, and being actuated by, a roller *c*¹ reciprocated by a pair of cam surfaces *c*², *c*³ during the rotation of the type-

cylinder *a*, whilst the dating mechanism is of the kind capable of hand adjustment.

e is the strip or web to be severed into ticket lengths as hereinafter described, the said web passing into the machine through the tubular guide *e*¹ and *f* is the impression roller of elastic material which is movable towards the type-cylinder *a* to press each ticket length against the required printing surfaces of the cylinder *a*. *f*¹, *f*², *f*³, *f*⁴, *f*⁵, *f*⁶ are the cams for effecting the printing movements of the impression roller *f* in conjunction with the printing surfaces *a*¹ to *a*⁶ respectively, and *g*, *h* are the cams for effecting the printing movements of the said roller *f* in conjunction with the printing surfaces *c*, *d* of the numbering and dating mechanisms, respectively. The cams *f*¹ to *f*⁶ and *g*, *h*, are attached to a cylinder *i* mounted on the shaft *b*, the cams *f*¹ to *f*⁶ being arranged across the face of the said cylinder, so that they rotate in different lateral planes, whilst the cams, *g*, *h* extend the full width of the said face for the purpose hereinafter described.

j indicates the series of main key-levers for determining the co-action of the impression roller *f* with any one of the denominational printing surfaces *a*¹ to *a*⁶, the key-levers corresponding, respectively, with the said surfaces, being indicated by the letters *j*¹ to *j*⁶. The said levers *j* are pivoted freely on a common pivot shaft *j*⁰ and extend through slots *j*⁷ in the casing *b*⁵, the bottoms of which slots determine the depression or operative movement of the said levers. *j*^{*} indicates springs for returning the key-levers *j* to their normal positions.

Each main key-lever *j* normally co-acts, through the medium of a double-armed catch *k* pivoted on the pivot *j*⁰ and common to all the said levers, with a tooth *k*¹ on a spring-controlled rocking quadrant *k*² pivoted at *k*³ and connected through the medium of an arm *k*⁴ in the manner hereinafter described, also pivoting freely at *k*³, and a link *k*⁵, with the rocking arm of blade *k*⁶ of an electric switch *k*⁷ controlling the supply of current to an electric motor, not shown, in driving connection with a sprocket wheel *k*⁸ freely rotatable on the shaft *b*. The said arm *k*⁴ is hereinafter referred to as the switch controlling arm. The arm or blade *k*⁶ of the switch *k*⁷ is pivoted at *k*⁹. Each key-lever *j* is formed with a notch *j*⁸ designed, when the said lever is depressed, to be engaged by an extension *j*⁹ on the electric switch arm *k*⁶ and to hold the said lever in the depressed position against the pull of its spring *j*^{*}. The sprocket-wheel *k*⁸ carries a clutch in the form of a notched or toothed wheel *l* designed to be engaged by a catch *l*¹, hereinafter termed the clutch-catch, which is pivoted to a driving arm *l*², for the type-cylinder *a*, the said arm being pivoted loosely on the shaft *b* and coupled to the latter through the medium of springs *l*³.

l³, l⁵ which act as buffers when starting and stopping the type-cylinder *a*. The said arm *l²* is formed at its outer end with a notch or bifurcation *l⁴* with which a tooth or projection *l⁶* on the outer end of the switch controlling arm *k⁴* is normally held in engagement by a stop or projection *l⁸* on the quadrant *k²* against the pull of a spring *l⁷*. The clutch-catch *l¹* when engaged with the clutch-wheel *l*, rotates or drives the type-cylinder *a*, but is normally obstructed by the tooth *l⁵* on the switch controlling arm *k⁴* so as normally to be held out of engagement with the said clutch-wheel. It will thus be seen that if any key-lever *j* be depressed, for instance, as indicated in Figure 10, it will come into contact with the catch *k* and release the latter from the tooth *k¹* on the quadrant *k²* which will be operated in the direction of the arrow, Figure 5, by its controlling spring *k⁹*, a distance determined by a second tooth *m* on the quadrant, offset slightly farther from the axis of rotation of the latter than the tooth *k¹*, this movement allowing the switch controlling arm *k⁴* to be moved by its spring *l⁷* to close the electric switch and engage the extension *j⁹* on the latter with the notch *j⁸* in the depressed key-lever, the movement of the said arm freeing the driving or buffer-arm *l²* and allowing the clutch-catch *l¹* to engage the clutch-wheel *l* and drive the type-cylinder *a* through a complete revolution, to effect the severing, printing, and delivery of a single ticket. At the end of this revolution, the notch *l⁴* of the buffer-arm will re-engage with the tooth *l⁵* on the switch controlling arm *k⁴*, which tooth will, owing to its being in the path of the clutch-catch *l¹*, disengage the latter from the clutch-wheel *l*. To bring the switch controlling arm *k⁴* into position for engaging with the notch *l⁴* in the buffer-arm *l²*, a cam *n*, hereinafter termed the release cam, in the form of a tooth or projection and keyed on the shaft *b*, will engage with a tooth *n¹* on the rocking quadrant *k²* and move the latter against the action of its spring sufficiently to allow, through the medium of the arm *k⁴*, the depressed key-lever *j* to be disengaged from the extension *j⁹* of the electric switch-arm *k⁶*, and allow the double-armed catch *k* to re-engage with the tooth *k¹* of the said quadrant again to hold the latter in the normal position, the switch blade *k⁶* being thus moved to the open position by the movement of the switch controlling arm *k⁴* under the action of the spring *l⁷* as the said arm re-engages the notch *l⁴* in the arm *l²*. As the switch controlling arm *k⁴* will, when the quadrant *k²* is moved to its normal position, be in the path of the end of the arm *l²*, the lower prong *l⁹* of the notch or bifurcation *l⁴* is arranged to be moved back against the pressure of a spring *l⁸* by impingement with the end of this said switch controlling arm *k⁴* and allow the latter to enter the said notch or

bifurcation. To ensure the full movement of each key-lever *j* when depressed, a surface *j¹⁰*, preferably shaped to the arc of a circle described from the common pivotal centre of the said key-levers, is formed just below the notch *j⁸*, against which surface, directly the quadrant *k²* is moved by the disengagement of the catch *k* from the tooth *k¹*, the extension *j⁹* of the switch-arm *k⁶* will be caused to bear and prevent the said arm closing the switch. This surface is formed at its lower end with a tooth *j¹¹* which would contact with the extension *j⁹* if the key-lever were released before having reached its lowest position and therefore could not resume its normal position. Figure 11 is a view showing a key-lever *j* depressed as in Figure 10 but the shaft *b* has turned through an angle of 90°. To effect the co-operation of the impression roller with the printing surface for the required denomination of ticket when such surface is in the printing position, a bar *o* carried at the outer end of a pair of arms on the pivot *j⁰* is arranged transversely of and beneath the whole series of key-levers *j¹* to *j⁸* with its upper edge *o¹* at a slight inclination to the common plane of the said key-levers, so that the latter are at different distances from the said upper edge and when depressed the levers *j²* to *j⁸* will lower the said bar in different degrees the bar *o* being unaffected by the lever *j¹*. One of the pivoted arms carrying the inclined edged bar is provided with an extension or lever-arm *o²* connected by a link *o⁴* and spring controlled lever *o⁵* with a member *p* slideable on a bar *p¹* and shown clearly in Figure 8, to which member the varying movements of the said bar *o* are imparted so as to move by a forked extension *p²* on the member, a roller *p³* at one end of a spring controlled double-armed lever *p⁴* pivoted on *p⁵* into the path of any one of the series of cams *f¹* to *f⁶*. The other end of the lever *p⁴* carries the impression roller *f*. The slide *p* also moves through the medium of another forked extension *p⁶* a roller *g* slidably mounted at one end of a spring controlled double armed lever *q¹* pivoted at *q²*, and the other end of which carries the inking roller *r* for all the printing surfaces of the type-cylinder *a*, so that the cam surfaces *f¹* to *f⁶* act upon the roller *g* to effect the inking of the printing surfaces *a¹* to *a⁶*; but, independent cams can be employed if desired. The pair of cams *g*, *h* hereinbefore referred to, extend the full width of the cylinder *a* to enable the rollers *p³* and *q* to be operated thereby whatever position the latter may have been moved into to co-operate with any one of the cams *f¹* to *f⁶* and they also serve to actuate the inking roller *r* to ink the type of the numbering and dating mechanisms *c*, *d*, respectively, during each rotation of the type-cylinder, although separate cams may be employed for this purpose, if desired. The cam

h for the dating mechanism is shown as being supported by an arm *s* pivoted at *s*¹ to the cylinder *i* so that it can be turned out of position either to be put out of action, or so that the impression roller *f* will be operated thereby so as not to co-act with the dating mechanism *d* when the latter is in the printing position. The inking roller *r* is itself inked by contact with the roller *r*¹ co-acting with the ink duct *r*², the said roller *r*¹ being rotated by sprocket gearing *r*³ and crank mechanism *r*⁴. The roller *r*¹ is shown as being arranged out of parallelism with the roller *r* but it may be in parallelism therewith, if desired.

v is the cam for severing the ticket lengths before they are printed, from the ticket strip *e* by the knife-blade *v*¹, pivoted at *v*² through the medium of the lever *v*³, pivoted at *v*⁴, and link *v*⁵, the said lengths being supported by a guide platform *v*⁶, and pressed thereon by a spring blade *v*⁷ the pressure of which can be varied by a screw *v*⁸.

The cam *v* also serves for operating co-acting double-armed levers *w* and *w*¹ for feeding the ticket strip *e* to the said knife by a pawl *w*² on the lever *w*¹ engaging holes *w*⁰ in the said strip *e*, spaced apart the length of a ticket in the known manner. The lever *w*¹ also serves, by a spring gripping device *w*³, pivoted at *w*⁴ and actuated by a link *w*⁵ having lost motion by a pin and slot connection *w*⁶ with the lever *w*¹, to feed each printed ticket into position partially to protrude through a discharge slit *x* in the case *b*⁴ of the machine, the ticket engaging with and being held between the jaws of another but fixed spring gripping device *x*¹. In Figure 9, a ticket is shown as having been placed by the gripping device *w*³ into the gripping device *x*¹, the latter, when withdrawn by the link *w*⁵, slipping over the ticket and leaving it in the said gripping device lying flat against the fixed jaw or guide *x*² of the device *x*¹, so that the said ticket allows of the placing in the protruding position, in contact therewith, of a second and third ticket without interference.

With the parts of the machine in the position illustrated in Figures 1 to 8, if one of the key-levers *j* be depressed, for instance, as indicated in Figure 10, it will move the catch *k* out of engagement with the hook *k*¹ of the quadrant *k*² so that the latter will be moved by its spring *k*³ in the direction of the arrow 1, Figure 5, and allow the spring *l*² to disengage the switch controlling arm *k*⁴ from the notch *l*⁴ in the driving or buffer arm *l*² to close the switch *k*⁶, *k*⁷, to energize the electric motor to drive the clutch wheel *l*, the disengagement of the said arm *k*⁴ from the arm *l*² allowing the catch *l*⁴ under the influence of its spring to engage with the said clutch wheel and drive the type-cylinder *a* in the direction of the arrow, 2, Figure 5. The de-

scribed movement of the arm *k*⁴ under the pull of the spring *l*² also causes the extension *j*³ of the switch blade *k*⁶ to engage with the notch *j*⁸ in the depressed key-lever *j*¹ and hold the latter in the depressed position. It will be noticed that the bar *o* is unaffected by the depression of the lever *j*¹, as the cam *f*¹ is already in line with the rollers *q* and *p*³ for effecting the inking and printing of the surface *a*¹, corresponding with the depressed key-lever *j*¹. The type-cylinder *a* in its rotation will bring the cam *g* into contact with, and move, the roller *q*, and consequently the lever *q*¹, to bring the inking roller *r* into contact with the type of the numbering device *c*. The cam *f*¹ will then also come into contact with the roller *q*, and effect the inking of the printing surface *a*¹. Simultaneously, or thereabouts, with the described rotation of the type-cylinder, the cam *v* will lower both the feed pawl *w*² out of engagement with the top-most hole *w*⁰ in the strip *e* to the next hole *w*⁰ below, and the ticket feed device *w*³, and then operate the knife *v*¹ to sever the ticket length determined by the said holes and held in the guide *v*⁶, the said device *w*³ being limited in its movement by an extension *w*⁸ thereon abutting against one of the tie-bars *b*³. The continued rotation of the cylinder *a* will bring the numbering printing surface *c* into the printing position opposite the impression roller *f* and the cam *g* into contact with the roller *p*³ to cause the said roller *f* to press the cut ticket length into contact with the said surface *c*, the said ticket length being fed upwards by the movement of the type-cylinder during the contact of the impression roller with the said ticket length, a distance equal to the length of the printing surface after which contact the ticket length remains stationary. Figure 11 shows the position of the parts just after the operation above referred to. The further rotation of the type-cylinder *a* will then bring the inked printing surface *a*¹ into the printing position, and, at the same time, the cam *f*¹ will cause the impression roller *f* to be again pressed into contact with the numbered ticket length to print the denomination or fare and feed the said ticket length between the spring pressed jaws of the feed device *w*³. The continued rotation of the cylinder *a* will then effect the inking of the type of the dating mechanism *d* and the movement of the impression roller *f* to effect the printing thereby by means of the cam *h*, similarly to the corresponding operations hereinbefore described in connection with the numbering device *c*, and the knife *v*¹ will be moved to its open position and the feed device *w*² and *w*³, respectively, moved upwardly to feed the ticket strip *e* the length of a ticket and to place the printed ticket into the gripping device *x*¹ so as to protrude through the slit *x* into position for use. Just before the

type-cylinder a completes its rotation, the release cam n will operate the quadrant k^2 by engagement with the tooth n^1 to release the depressed key-lever j^1 and allow the parts 5 to resume the normal position and cut off the current to the motor.

The means for preventing more than one of the key-levers j from being operated at a time, advantageously comprise a series of 10 plates t, t arranged side by side in a common plane below the said key-levers and confined between a pair of lateral stop surfaces. In the drawings, these stop surfaces are formed by the frame plates b^2 . The distance between 15 these stops is equal to the sum of the widths of all the plates t , and the thickness of a key-lever, so that only one of the said levers, when depressed, can pass between a pair of the said plates, the remaining plates exactly 20 filling the spaces between the depressed key-lever and the stops, and therefore forming obstructions to the passage of any other key-lever j . The plates are shown mounted on and depending from pivots t^1 , but they may 25 be arranged to slide laterally.

u, u^1 are the additional key-levers supported on each of the key-levers j to enable the printing and delivery of more than one ticket of each denomination or fare to be effected. 30 These key-levers u, u^1 have downward extensions u^2, u^3 , respectively, of different lengths extending below the levers j and are pivoted on a common pivot u^4 and arranged in the same plane as the key-levers j carrying 35 them, so that, when either of them is depressed, it will actuate the supporting key-lever j the full extent of its movement, determined by the slot j^7 in which it works, the said key-levers u, u^1 acting against springs 40 u^5, u^6 , respectively. The key-levers u serve to determine the printing and delivery of two tickets of each denomination and the lever u^1 of three tickets, so that if two tickets of one denomination are required, one of the 45 levers u must be depressed, when it will first be moved on its pivot and then come into contact with and move the key-lever j on which it is pivoted, its pivotal movement causing its extension u^2 to move into position 50 over the outer end of the catch k so that further depression of the said lever u will move the said catch out of engagement with the tooth k^1 of the quadrant k^2 and through a greater arc than if moved only by the said 55 supporting key-lever j , the latter having further to travel, before meeting the said catch, than the extension u^2 . The said quadrant is thus allowed to be operated by its controlling spring, but, instead of being arrested by 60 the second offset tooth m , a third tooth m^1 is provided on the quadrant for its arrest, the said tooth being offset or arranged slightly farther from the axis of rotation of the said quadrant than the said second tooth m .

65 This tooth m^1 , engaging with the catch k ,

allows slightly greater rotation of the quadrant on its axis under the influence of its controlling spring, than if actuated by a lever j for the delivery of a single ticket, so that the cylinder a will be rotated twice to 70 effect the printing and delivery of two tickets, the said cylinder during the first rotation, moving back the quadrant k^2 by the engagement of the release cam n with a second tooth n^2 on the quadrant, the said backward 75 movement being only sufficient to allow the catch k to engage with the second offset tooth m , so that the cylinder is free to make another revolution to print and deliver a second ticket when the quadrant will be caused, by the co-action of the cam n and tooth n^1 , to resume its initial position and operate the electric switch to cut off the supply of current. The key-lever u^2 for determining the 80 printing and delivery of three tickets is formed with its extension u^3 slightly longer than the extension u^2 of the key-lever u^1 , so that the catch k will be moved through a greater arc than when moved by the key-lever u , the toothed quadrant, when released 85 by the said catch, being arrested in its movement by a fourth tooth m^2 , which is offset or arranged slightly further from the axis of rotation of the quadrant than the third tooth. A third tooth n^3 is provided on the quadrant 90 for co-action therewith of the release cam n , in order that the cylinder a shall rotate three times, and thus print and deliver three tickets, before resuming its normal position. 95

From the foregoing it will be seen that the teeth n^1, n^2, n^3 on the quadrant k^2 serve for the successive engagement therewith of the release cam n to move back the said quadrant against the action of its spring a distance of each of the successive offset teeth thereon for 100 each rotation of the type-cylinder a , until the quadrant reaches its normal position, the catch k acting as a detent and preventing any forward movement of the quadrant between the actions of the said release cam. 105

y is the numerator or counter in connection with each key-lever j for indicating the number of tickets issued under the manipulation thereof, the operation arm y^1 of each of which numerators is designed to be rocked by the cam through the medium of an arm y^2 on the lever v^3 and a spring controlled link y^3 through the medium of a frame y^4 swinging on a pivot y^5 and carrying a series of double-armed levers y^6 corresponding in number to the key-levers j and having one end connected thereto by a link y^7 , whilst the other end is pivoted to the operating arm y^1 by a pin and slot connection y^8 , so that it is only when a key lever j is fully depressed that the connected operating arm y^1 will be rocked by the cam v through a sufficient arc to effect an indication by the numerator having the said arm. 115

z is the numerator for indicating the total 120

number of tickets issued by the machine, the operating arm z^1 of which numerator is connected by a link z^2 to the aforesaid swinging frame y^4 so as to be actuated each time the type-cylinder is rotated.

5 Instead of employing the cam v for operating the numerators, an independent cam can be employed.

Although I have described the machine as 10 constructed for the printing and delivery of six different denominations of tickets, it is to be understood that it may be constructed to print and deliver more or less than the said number, and that I do not restrict myself 15 to the arrangement of numbering and dating mechanism as I may dispense with the latter, and where tickets are printed with duplicate portions, two numbering devices may be employed.

20 What I claim is:—

1. In a printing machine, a rotatable type cylinder having a series of printing surfaces circumferentially arranged on its periphery, an impression member movable toward and 25 away from the periphery of the cylinder, means for positioning a strip to be printed, between the cylinder and impression member, a series of cams movable in unison with the cylinder, the number of cams being equal to 30 the number of printing surfaces, and the cams being arranged to accord with the arrangement of the printing surfaces, actuating means for the impression member provided with an element adapted to be shifted 35 so as to be positioned in the path of movement of any selected one of the cams, and manipulative means for shifting said element.

2. In a printing machine, a rotatable type cylinder provided on its periphery with a 40 circumferentially arranged series of printing surfaces, an impression member movable toward and away from the periphery of the cylinder, means for positioning a strip to be printed, between the cylinder and the impression member, a series of cams movable in unison with the cylinder and arranged side by side, the number of cams being equal to 45 the number of printing surfaces and being arranged to accord with the arrangement of the printing surfaces, actuating means for 50 the impression member, including an element shiftable across the paths of movement of the cams, and manipulative means for shifting said element into the path of movement of any one of said cams, whereby 55 when the latter rotate, the impression member will move the strip toward a selected one of the printing surfaces.

3. In a printing machine, a rotatable type 60 cylinder having a series of printing surfaces circumferentially arranged on its periphery, means for rotating said cylinder, an impression member movable toward and away from the periphery of the cylinder, means for positioning a strip of material to be printed, be-

tween the impression member and the cylinder, a printing drum carried by the cylinder, means for moving the impression member toward the cylinder when the printing drum is opposite the impression member, and key 70 controlled means for moving the impression member toward a selected one of the printing surfaces as the cylinder rotates, whereby the strip may be brought into contact with a selected one of the printing surfaces.

4. In a printing machine, a rotatable type cylinder provided on its periphery with a circumferentially arranged series of printing surfaces, printing drums carried by the cylinder and projecting into the peripheral line 80 of the latter, an impression member movable toward and away from the periphery of the cylinder, a series of cams movable in unison with the cylinder, the number of cams being equal to the number of printing surfaces, 85 plus the printing drums, actuating means for the impression member including an element shiftable across the paths of movement of the cams, the cams corresponding with the drums being adapted to operate the shiftable element each time the cylinder is rotated, and manipulative means for shifting said elements into the path of movement of any one of the cams corresponding to the printing surfaces.

5. In a printing machine, a rotatable type cylinder, a series of movable keys, a pivotally mounted bar having an inclined edge which may be engaged by the keys for swinging the bar varying degrees, a shiftable carriage, means operatively connecting the carriage to said bar, whereby when a key is actuated, the carriage will be shifted a certain degree, an abutment movable with the carriage, a series of cams movable in unison 105 with the cylinder and arranged side by side, said abutment being moved by the carriage into the paths of movement of the cams for causing the abutment to be actuated by a cam corresponding to the particular key actuated, an impression roller actuated by said abutment, and means for feeding a strip to be printed, between the impression roller and the cylinder.

6. A printing machine as claimed in claim 110 5, including an inking roller cooperable with the type cylinder, a bell-crank lever carrying the inking roller, a second abutment carried by the bell-crank lever and adapted to be actuated by any one of said cams, and means connecting the first mentioned abutment to the second abutment for shifting the abutments in unison.

7. In a printing machine, the combination 115 with a type cylinder and an impression roller movable toward and away from the same, of means for feeding a strip to be printed between the cylinder and roller, said means including a strip guide, a pawl for moving the strip along said guide, a lever movable 120

in unison with the cylinder for actuating said pawl, a strip receiving platform cooperating with the guide, means between the guide and platform for severing the strip 5 into ticket lengths, said platform being located anterior to the impression roller, a spring gripping device arranged posterior to the impression roller and adapted to grasp a ticket after it has passed between the roller and cylinder, a movable member carrying the spring gripping device, and a link 10 connecting the movable member to the pawl actuating lever.

8. In a printing machine, the combination 15 with a type cylinder and an impression roller movable toward and away from the cylinder, of means for feeding a ticket between the roller and cylinder, a spring gripping device for withdrawing a ticket from between the roller and cylinder, a ticket delivery port, an apron cooperating with the spring gripping device for guiding a ticket through said port, and a spring pressed latch 20 cooperating with the apron to grip tickets delivered to the port by the spring gripping device.

9. In a printing machine, key controlled means, a rotatable type cylinder, a counter for each key of the key controlled means, a 30 slotted actuating arm for each counter, a double-armed lever for each counter arm, each double-armed lever having a pin engaging the slot of the counter arm with which it cooperates, a movable member supporting 35 the double-armed levers, links connecting the keys with the double-armed levers, and means operatively connected to the movable member and movable in unison with the type cylinder for causing the actuation of the 40 counter corresponding to an actuated key.

10. A printing machine including a rotatable type cylinder having printing surfaces for different denominations of tickets arranged in alignment around its periphery, an impression roller movable with respect to the type cylinder for pressing a ticket to be printed against a selected one of said printing surfaces, and manually operable key controlled mechanism for causing 45 the impression roller to press a ticket against any selected one of said printing surfaces as the cylinder rotates, said type cylinder being movable with respect to the manually operable mechanism.

55 11. A printing machine as claimed in claim 10, in which the type cylinder is also provided with a peripherally arranged date printing surface, and means controlled by said manually operable mechanism for causing the impression roller to press a ticket against said date printing surface.

12. A printing machine as claimed in claim 10, in which the type cylinder is provided with a peripherally arranged numbering printing surface, and means movable in uni-

son with the type cylinder for causing the impression roller to move a ticket toward the type cylinder each time the numbering printing surface is opposite the impression roller during the rotation of the cylinder.

13. A printing machine as claimed in claim 10, wherein the manually operable mechanism includes cooperating elements adapted to cause the printing and successive delivery of more than one ticket of each denomination 70 of the machine is capable of printing.

14. A printing machine as claimed in claim 10, in which the type cylinder is provided with a rotatable shaft, the manually operable mechanism including a series of cams arranged around the shaft and rotatable with the latter, the number of said cams corresponding to the number of the printing surfaces on the type cylinder, a series of key levers corresponding in number to the printing surfaces on the type cylinder, and means whereby the operation of any key lever will bring the impression roller into operative connection with the cam of said series corresponding to said actuated key lever, to print a ticket when the selected printing surface arrives in the printing position.

15. A printing machine as claimed in claim 10, in which the manually operable mechanism cooperates with a series of cams movable with the type cylinder and corresponding in number to the printing surfaces, an inking roller cooperating with said surfaces, and means actuated by the cams and controlled by the manually operable mechanism for bringing the inking roller into contact with a selected one of the printing surfaces.

16. A printing machine as claimed in claim 10, in which the type cylinder is provided with a numbering printing surface, a cam movable in unison with the cylinder, an inking roller adapted to apply ink to the numbering printing surface, and means actuated by the cam for causing the inking roller to engage the numbering printing surface, as 105 the type cylinder rotates.

17. A printing machine as claimed in claim 10, including a dating printing surface peripherally arranged on the type cylinder, a cam movable in unison with the type cylinder, inking means for applying ink to the dating printing surface, and means actuated by the cam during the rotation of the type cylinder for moving the inking means into contact with the dating printing surface.

18. A printing machine as claimed in claim 10, in which date printing mechanism is peripherally arranged on, and carried by the type cylinder, a cam movable in unison with the type cylinder, and adapted to move the impression roller toward the type cylinder, said cam being movably mounted on the type cylinder, whereby the cam can be put out of action or moved, for the purpose set forth.

19. A printing machine as claimed in claim 130

- 10, in which the manually operable mechanism includes a series of keys, and a numerator operatively connected to each key to record the number of actuations thereof.
- 6 20. In a printing machine, a type member provided with a plurality of printing surfaces, means for feeding a strip of material to be printed, means for severing sections from the strip, and manually controlled 10 means for effecting a cycle of operation of the machine whereby the previously positioned strip is first severed and then brought into engagement with a selected printing surface, and the strip re-positioned ready for 15 severing therefrom a section to be printed during the succeeding cycle.
21. In a printing machine, a movable type member provided with a plurality of printing surfaces, means for feeding a strip of 20 material to be printed, means for severing sections from the strip, and manually controlled means for effecting a cycle of operation of the machine, whereby a severed section is brought into engagement with a selected 25 printing surface while the latter is in motion, and said strip is fed and re-positioned ready for another section to be severed therefrom to be printed during the succeeding cycle.
- 30 22. In a printing machine, an electric motor driven rotatable type member having a plurality of successively arranged printing surfaces, an impression member, means for feeding a strip of material to be printed, between said members, control mechanism for the electric motor which drives the type member, selective manually controlled means for moving one of said members toward the other member for bringing any one of said printing surfaces into contact with said strip while the type member is rotating, and means operatively connecting the selective manually controlled means to the motor control mechanism.
- 45 23. In a printing machine, a rotatable type cylinder carrying a series of printing surfaces, means for presenting material to be printed to the cylinder, keys operable to effect printing by a selected one of the printing surfaces, a latch normally locking the cylinder against rotation, means actuated by the keys for releasing the latch, said cylinder being adapted to be actuated by an electric motor, a switch to control said motor, means 50 operatively connecting the switch to the key actuated means, whereby when the latch is released, the switch will be closed, a member movable in unison with the cylinder, and means actuated by the last mentioned member for operating the key actuated means after a revolution of the cylinder, and for re-latching the cylinder and thereby opening said switch.
- 55 24. In a printing machine, an electric motor operated rotatable type cylinder carrying a series of printing surfaces, means for presenting material to be printed to the cylinder, keys operable to effect printing by a selected one of the printing surfaces, a latch normally locking the cylinder against rotation, a normally open switch for controlling said motor, means actuated by the keys for releasing the latch and closing the switch, a member movable in unison with the cylinder, and means actuated by said member for returning the latch to latching position and for opening the switch after the cylinder rotates.
- 60 25. In a printing machine, a rotatable type cylinder carrying a series of printing surfaces, means for presenting material to be printed to the cylinder, a member normally holding the latch in latching position, means for normally holding said member in the position in which it keeps the latch in latching position, keys operable to effect printing by a selected one of the printing surfaces, means actuated by the keys for releasing the last mentioned means to permit the holding member to release the latch to allow the cylinder to rotate, and a member rotatable with the cylinder and adapted to actuate the last mentioned means for restoring the holding member, latch and key actuated means to normal position.
- 65 26. In a printing machine, an electric motor operated rotatable type cylinder carrying a series of printing surfaces, means for presenting material to be printed to the cylinder, keys operable to effect printing by a selected one of the printing surfaces, a normally open switch for controlling said motor, a latch normally locking the cylinder against rotation, means actuated by the keys for releasing the latch and closing the switch, a member operable in unison with the cylinder, means actuated by said member for returning the latch to latching position and for opening the switch after the cylinder rotates, said key actuated means including a key extension, and means connected to the switch and engageable with said extension for holding the latter against movement until the switch is thrown to open position.
- 70 27. In a printing machine, an electric motor operated rotatable type cylinder carrying a series of printing surfaces, means for presenting material to be printed to the cylinder, keys operable to effect printing by a selected one of the printing surfaces, a normally open switch for controlling said motor, a latch normally locking the cylinder against rotation, means actuated by the keys for releasing the latch and closing the switch, a member operable in unison with the cylinder, means actuated by said member for returning the latch to latching position and for opening the switch after the cylinder rotates, said key actuated means including an extension provided with a detent, and a member movable with the switch and engageable with
- 75 80 85 90 95 100 105 110 115 120 125 130

- the detent for preventing the switch from closing in case a key is not moved to a sufficient degree to release the latch. 28. A printing machine as claimed in claim 27, in which the key actuated means includes a pivotally mounted bar, keys engageable with said bar for moving the latter, each of said keys supporting an auxiliary key, and each auxiliary key having a movable extension adapted to engage and move the bar when either of said auxiliary keys is actuated. 29. In a printing machine, a rotatable type cylinder carrying a series of printing surfaces, means for presenting material to be printed to the cylinder, keys operable to effect printing by a selected one of the printing surfaces, a movable clutch member, a pivoted arm provided with a lug engageable with the clutch member for normally preventing the cylinder from rotating, a toothed member normally holding said lug in latching position, a spring for moving the toothed member in one direction for releasing said lug, spring means for moving the lug out of latching position, means actuated by the keys for normally holding the toothed member in position to cause the lug to engage the clutch member, and a member movable in unison with the cylinder, and adapted to actuate the toothed member for restoring the lug, clutch member and key actuated means to normal positions. 30. In a printing machine, a type member provided with a series of successively arranged printing surfaces, an impression member positioned in close proximity to the first mentioned member, means for feeding a strip of material to be printed between said members, and key controlled means for effecting rotation of the type cylinder and for moving one of the members toward the other member to bring the material to be printed into contact with any selected one of said printing surfaces. 31. In a printing machine, a type member having a curved face provided with a series of successively arranged printing surfaces, an impression member mounted in close proximity to the type member, means for feeding a strip of material to be printed, between said members, and key selected means for effecting rotation of the type cylinder and for moving one of the members toward the other when any selected one of said printing surfaces is opposite to the impression member. 32. In a printing machine, a type member provided with a peripheral face having a series of printing surfaces thereon, an impression member movably mounted adjacent to the type member and adapted to move toward and away from said peripheral face, means for turning said type member, a series of normally stationary keys, and means selected thereby for initiating movement of the type member and for causing the impression member to move toward the type member at a time when any selected one of the printing surfaces is opposite to the impression member. 70
